FALLER GUIDE FOR GILL BOXES

Robert Gärtner, Ingolstadt, Germany, assignor to Deutscher Spinnereimaschinenbau Ingolstadt Niederlassung der Schubert & Salzer Maschinenfabrik Aktiengesellschaft, a corporation of Germany

Filed Nov. 25, 1955, Ser. No. 549,066

Claims priority, application Germany Dec. 2, 1954

7 Claims. (Cl. 19—129)

This invention relates to new and useful improvements in the faller guide construction for gill boxes and intersecting gill boxes in which the fallers are horizontally advanced and retracted by means of screws and in which hammers are arranged at the ends of these screws for the vertical displacement of the fallers in their end position from their working position to their return position and vice versa.

In the prior known construction of faller drives of intersecting gill boxes of this type the transfer of the faller after it had passed into its end position was effected upon impact by rotating hammers acting on the faller ends. Upon this striking the faller would be thrown against the slide rails or comb guides which limit its vertical motion and would be abruptly stopped upon coming into contact with these parts. In the case of gill boxes the knocking of the fallers out of their operating position into their return position took place in the same manner with a violent impact upon the hitting of the hammer against the faller ends and upon the coming of the faller ends against the horizontal slide rails. As a result of these impact-like forces to which these conventional fallers and their guides were subjected, extensive wear of the stop and slide surfaces would occur and the gill boxes would be noisy and vibrate in operation.

Various attempts have been made to dampen the striking of the hammers against the faller ends. In accordance with one proposal, as set forth in German Patent No. 451,222, the impact surfaces at the ends of the fallers were shaped so that the hammer would come in sliding contact therewith. In order to reduce the striking of the fallers against their slide rails, various resilient means have been proposed such as buffer springs, and leather or rubber buffers. Similar measures used in connection with the striking hammers have proven somewhat effective provided that the speed of the gill box and the number of faller lifts is not too excessive. In the case of rapidly operating gill boxes, however, having for example, 1,000 or more faller lifts per minute there takes place despite the aforementioned expedients, heavy impacts, high wear and a chattering and canting of the fallers moving back and forth between the hammer and slide rail which impairs a clean vertical insertion into the fiber material to be drawn and an impact-free removal of the pins from the sliver and which will not permit continuous operation of the gill box with satisfactory drawing.

One object of this invention is to overcome the above mentioned disadvantages while allowing an increased speed and capacity of the gill box. This and still further objects will become apparent from the following description read in conjunction with the drawings in which:

Figs. 1 through 4 diagrammatically show an embodiment of a faller end guided between an acceleration cam and braking cam in accordance with the invention viewed in the direction of the axis of the screw in four different stages of the vertical displacement of the faller end from its return position to its operating position.

Fig. 5 is a diagrammatic perspective view showing the

2

movement of the faller guide of an intersecting gill box.

Fig. 6 is a diagrammatic side elevation viewed in the direction of the axis of the screw showing an arrangement of fallers in an intersecting gill box,

Fig. 7 is a side elevation showing an embodiment of a butting or initial running-on surface forming a continuation of the threads of the advance or return screw in accordance with the invention which serves to introduce or brake the horizontal motion of the fallers,

Fig. 8 is a plan view of the running-on surface shown in Fig. 7,

Fig. 9 is a side elevation showing a pair of cams and a faller end in accordance with the invention as arranged on the advance and return screw and having a connected running-on surfaces as shown in Figs. 7 and 8, and

Figs. 10 and 11 are diagrammatic side elevations viewed in the direction of the screw spindle of embodiments of fallers and slide rails in accordance with the invention.

In accordance with the invention, each individual faller is so raised or lowered into its return position at the end of the drawing field after completing its horizontal motion, that it is accelerated during the first part of its vertical displacement by means of a rotating accelerating cam continuously and without impact from its rest position, moving from zero speed, up to its maximum speed, and is thereupon, during the second part of its vertical displacement, supported by a retarding or decelerating cam and so controlled or decelerated that its lifting speed continuously decreases and then drops to zero as soon as the faller has reached its return position.

For this purpose, both faller ends are so developed that their narrow sides facing the needle field, in connection with the fallers which are in operating position, rest against the spindles of the two advancing screws, and at the end of the pin field, after the completion of the horizontal movement are grasped completely free of impact, by means of slide surface for the acceleration cams provided tangentially on the screw spindle, and thereupon continuously accelerated and displaced in vertical direction.

With the accelerating cam arranged on the end of the advance screw, there cooperates the braking cam seated on the front end of the corresponding return screw. This latter cam enters into operation in particular during the second portion of the vertical movement of the faller in that it continuously moves the faller end, corresponding to its slide path tangentially meeting the spindle of the return screw to said spindle and in this connection gradually reduces the speed to zero. The lifting cams seated on the end of the return spindle act in a similar manner and cooperate with the braking cams arranged at the start of the advance spindle and associated with them, and return the individual fallers from their return position into their operating position without impact.

In this way the two ends of each individual faller during its vertical transference from the operating position into the return position and vice versa are no longer, as heretofore customary, guided only on one side by means of the accelerating cam but, rather, they are now positively guided in a locked manner, free of impact, on both sides between an accelerating cam and a retarding or braking cam cooperating with same, over the entire vertical path. In this way the previous disadvantage of the faller and being accelerated abruptly by the impact received from the accelerating cam, moving away from the hammer and continuing its further path until striking against the slide rail without control, is avoided. Instead of the heretofore unavoidable, uncontrolled acceleration of the fallers in vertical direction, there is an impact-free lifting or lowering motion controlled by the guide surfaces of the

60 accelerating cam but, rather, they are now positively guided in a locked manner, free of impact, on both sides between an accelerating cam and a retarding or braking cam cooperating with same, over the entire vertical path. In this way the previous disadvantage of the faller and being accelerated abruptly by the impact received from the accelerating cam, moving away from the hammer and continuing its further path until striking against the slide rail without control, is avoided. Instead of the heretofore unavoidable, uncontrolled acceleration of the fallers in vertical direction, there is an impact-free lifting or lowering motion controlled by the guide surfaces of the

pair of cams, which surfaces are constantly in contact with the faller end.

In accordance with another feature of the invention, the horizontal advance motion transmitted to the fallers by the return and advance screws, in the same manner as their vertical motion is introduced by means of bent, suitably developed guide surfaces arranged on the ends of the screws, in which connection the fallers are first of all continuously accelerated to the proper amount of forward motion and, at the end of their horizontal path, are retarded and stopped in the same manner before the raising or lowering motion starts. In accordance with a still further feature of the invention measures are also provided for the insertion of the fallers in a suitable manner between the screws and for their removal again from the gill box if necessary.

Referring to the drawings in Figs. 1 to 4 which may represent the lower faller of an intersecting gill box or the faller of an ordinary gill box, the advance screw or worm is designated 1 and the return screw or worm 2; the accelerating cam is designated I, the braking or retarding cam II, and the faller end 3 is guided in a form-locked manner between these two cams.

In Fig. 1 the faller is still in its operating position at the end of the field of pins, just before the commencement of its vertical displacement downward into its return position. The faller end 3 has therefore reached the end of the thread of the advance screw rotating in the direction indicated by the arrow P and at this place its edge 3' facing the pin field comes into contact with the slide surface I of the advance screw 1, which surface is tangentially connected to the screw spindle 1'. The slide surface II of the retarding cam seated at the end of the return screw 2 has at this moment just reached the narrow sides 3" of the faller end. Upon further turning of the two screws and cams in the direction indicated by the arrow P, the faller end 3 which at first, as shown in Fig. 1, is still resting against the screw spindle 1' of the advance screw is grasped by the slide path I of the rotating accelerating cam. Since this slide path I terminates tangentially in the cylindrical surface 1' of the spindle, the vertical impact-free motion of the faller in the direction indicated by the arrow A commences. The faller end 3 is therewith, as shown in Figs. 2 and 3, moved further until it comes into its return position, shown in Fig. 4. The individual stages of this downward motion are shown in Figs. 2, 3 and 4, together with the corresponding positions of the cam pairs which guide the faller end. At the end of this downward motion the faller end 3, as shown in Fig. 4, passes from the slide surface II of the braking cam, which terminates tangentially into the cylindrical surface of the screw spindle 2', without impact, into the return position of the faller, whereupon its horizontal return motion is introduced by means of the running-on surface 4 shown in Figs. 7, 8 and 9. The return screw thereupon takes over the return motion of the faller.

The entire movement of the fallers is shown in Fig. 5. In this diagrammatic representation, the pairs of cams arranged on the ends of the screw pairs 10, 20, 1u, 2u as well as the running-on surfaces which introduce and brake the horizontal displacement of the fallers 30 and 3u respectively are not shown in order to simplify the illustration. In the left upper fourth of this figure, there are shown at B and V the accelerating and retarding sections respectively of the vertical faller motion controlled by the pairs of cams and at B' and V' the accelerating and retarding sections respectively, influenced by the running-on surfaces, of the horizontal forward and return motion of the left faller end of an upper faller 30.

In Fig. 6 there is shown the arrangement of the fallers in the case of an intersecting gill box.

Figs. 7, 8 and 9 show how the lateral running-on surfaces 4 are arranged on the cams I, II. When the cam is rotating they catch the faller end brought in the direction

indicated by the arrow W by means of the rotating screw on its spindle end without impact or they introduce, in the direction of the arrow W', the start of the horizontal motion of the faller.

5 The running-on surfaces, as may be noted, merely constitute a continuation of the screw thread running along the cams and decreasing in pitch in the direction away from the central portion of the screw so that, as the faller runs off from the screw onto the running-on surfaces, 10 its horizontal motion, in the direction W, constantly decreases to zero and as the same moves from the running-on surface on to the screw in the direction W', its horizontal motion steadily increases from zero until it reaches the velocity that will be imparted by the screw as it runs onto 15 the screw. These running-on surfaces thus replace the otherwise customary resilient guide bars, known as "comb guides" at the striking places of the fallers. It is possible to do without these striking surfaces 4 on the pairs of cams, in which case the pairs of cams I, II in accordance 20 with the invention then cooperate with the known guide bars provided with shock absorbing means.

The gill boxes are provided with a slide rail in order to maintain the fallers in engagement with the threads of the screw during the horizontal motion. In certain 25 of the figures the slide rails have not been shown for convenience of illustration. The slide rail 5 is illustrated, however in Figures 10 and 11. It extends parallelly between the screws 1 and 2 over the length of the screws, terminating at the screw end so that the fallers can effect 30 their vertical motion past the slide rails.

From Fig. 10 there can be noted the manner in which a faller can be inserted or removed. For this purpose, the slide rail 5 arranged between the fallers 3a which are in operating position and the fallers 3r which are 35 in return position is pulled back by means of a holding member serving for its support, for example, the pin 6, horizontally into the position 5' shown in dotted line, whereupon it is possible to bring the other end of the faller to be inserted into the position 3a shown in dotted line. This makes it possible to insert the other faller end, not shown in the drawing, into the screw corresponding to it, whereupon the faller 3a is pushed back into its operating position, shown in solid line, and secured in the operating position by pushing the slide 40 rail forward into the position 5 in such a manner that the faller 3a cannot slide out of the advance screw 1. The slide rail 5 at the same time also secures the fallers 3r which are in the return position.

50 In Fig. 11 there is shown another possible development of the faller end, which makes possible the movement and supporting of the fallers in the same manner.

While the invention has been described in detail with reference to the specific embodiments shown, various changes and modifications will become apparent to the skilled artisan which fall within the spirit of the invention and the scope of the appended claims.

I claim:

1. In a gill box having horizontal advance and return screws and a faller movable horizontally along said 60 screws upon rotation thereof and vertically between the screw ends from the advance screw to the return screw at one end and from the return screw to the advance screw at the other end, the improvement which comprises a separate acceleration cam positioned at said first mentioned end of said advance screw and said second mentioned end of said return screw and a separate braking cam positioned at said second mentioned end of said advance screw and said first mentioned end of said return screw, said acceleration cams and braking cams being shaped and dimensioned to hold and guide the faller therebetween over its path of vertical motion, the acceleration cams being shaped to accelerate the faller over a first portion of its vertical motion, and said braking cams being dimensioned to decelerate the faller of

the remaining portion of its vertical motion to about zero velocity at the screw spindles.

2. Improvement according to claim 1 in which the surface of each cam terminates tangentially at the spindle of the screw on which it is positioned.

3. Improvement according to claim 1 in which said cams define running-on surfaces extending as a continuation of the threads of the screws on which the cams are positioned and decreasing in pitch the direction away from the central portion of the screw.

4. Improvement according to claim 1 including a slide rail positioned between said advance and return screws extending parallel thereto for maintaining the faller in engagement with the threads of said screw.

5. Improvement according to claim 4 in which said slide rail is laterally movable for the insertion or removal of a faller.

6. In a gill box having horizontal advance and return screws a faller movable horizontally along said screws upon rotation thereof and vertically between the screw ends from the advance screw to the return screw at one end and from the return screw to the advance screw at the other end and means for breaking the forward inertia of the faller bars at the end of the advance screws

which means stop the horizontal progress of the faller bars as they leave the advance screws, the improvement which comprises a separate acceleration cam positioned at said first mentioned end of said advance screw and said second mentioned end of said return screw, said acceleration cams being shaped and dimensioned to accelerate the faller over a first portion of its vertical motion and having a cam surface which terminates tangentially at the spindle of the screw to which it is attached.

7. Improvement according to claim 6 in which said cams define running-on surfaces extending as a continuation of the thread of the screw on which the cam is positioned and decreasing in pitch in the direction away from the central portion of the screw.
